FILM MARKING SYSTEM

John Watson Jones, Jr., Los Angeles, Calif., assignor to Radio Corporation of America, a corporation of Delaware

Application October 12, 1943, Serial No. 505,919

9 Claims. (Cl. 179—100.3)

This invention relates to motion picture sound apparatus and particularly to a system for marking, identifying, or cueing a motion picture film while in motion through a camera, recorder, projector, or sound reproducer.

In the production of motion picture sound films, the picture and sound are usually photographed and recorded on separate films in the first instance and then reproduced simultaneously in individual reproduction apparatus before combination onto the final composite film. This is done for several reasons, such as to permit the combining of other sound tracks, such as sound effects with the dialogue, to correct irregularities in the dialogue track, and to obtain the proper level and certain dramatic effects. In this rerecording process, as it is called, the picture is projected on a screen in front of one or more operators called "mixers," and the sound track is simultaneously reproduced, the mixers adjusting the volume and introducing the various sound effects at the proper points. Several rehearsal runs are made prior to the final "take," which consists of the recording of a new sound record combining the various separate records.

During the rehearsals, the dialogue track and frequently the sound effect tracks are found to produce unwanted sounds, and it is necessary to note the point or points in the particular track reel at which such sounds are produced. After inspection of these points, modifications or corrections may be made. Deleterious noises are introduced by scratches and holes in the sound record or other variations in the record, which introduce noise in the form of "swishes" or "plops." Many times these noises may be reduced by painting over the record. The reduction of excessive sibilant sounds may also be accomplished by inking them over at the proper point on the original sound track to increase the average density of the track. Points on the sound tracks being reproduced where insertions are to be made or certain portions are to be deleted must also be noted.

The present invention is directed to a system for enabling the mixer to mark any one film being reproduced or all of the films simultaneously during the reproduction of the films at the point to be inspected and possibly modified. One of the standard methods of locating inspection points is to "paper" films, which consists in the mixer giving an order over an intercommunication system to the operator at the reproducer to insert a piece of paper in a certain film reel, which paper is wound up in the reel. It is real-

ized, of course, that when the reel is unwound, that the paper will not be at the exact point producing the trouble, and it is necessary to search for it. This consumes considerable time, and it is often difficult to locate the exact point in question.

Another more accurate method of determining the inspection point is disclosed and claimed in T. C. Sharp U. S. Patent No. 2,338,014, of December 28, 1943. In the disclosure of this patent, the mixer notes on a footage counter run in synchronism with the picture and sound films, the footage of the film at the point to be inspected. In rewinding the films, this footage mark must be found to locate the desired point.

In the present invention, a switch button is located adjacent the mixer's potentiometer controlling the amplitude of the sound from a particular reproducer, and if an inspection of any point in the track or film in that particular reproducer is desired, it is only necessary for the mixer to push the button adjacent his dial which automatically places a mark on the film at or immediately adjacent the exact point to be inspected, this mark being either in the form of an ink or crayon mark. In the case of sound films without pictures, this mark can be of considerable width and positioned in the center of the sound track. If a picture film or a film on which a picture is to be printed is to be marked, the mark may be applied along the sprocket holes or on the area outside the sprocket holes. Since the mark is placed on the film shortly after the translation point or the point at which the sound film is scanned by the reproducing light beam, the application of the mark is generally placed at the exact point at which the modification is to be made.

The principal object of the invention, therefore, is to facilitate the marking of sound motion picture films during projection and reproduction.

Another object of the invention is to facilitate the rerecording of sound tracks.

Another object of the invention is to provide a marking or identification system which will mark a film during projection or reproduction at the exact point at which the film is to be inspected.

A further object of the invention is to provide a marking system for a film in motion, which may be operated from a remote point.

A still further object of the invention is to provide a film marking system for a sound film being reproduced which will place a mark at or

immediately adjacent to the point to be inspected during movement of the film.

Although the novel features which are believed to be characteristic of this invention will be pointed out with particularity in the appended claims, the manner of its organization and the mode of its operation will be better understood by referring to the following description read in conjunction with the accompanying drawing forming a part hereof, in which:

Fig. 1 is a diagrammatic illustration of a sound film reproducing system for rerecording purposes which embodies the invention.

Fig. 2 is a plan view partially in cross-section of the marking unit of the invention.

Fig. 3 is a schematic drawing of the circuit arrangement for the marking system, and,

Fig. 4 is a detailed view showing a modification of the marking element of Fig. 2.

Referring now to the drawing in which like numerals identify the same element, a console 5 having a neon type of volume indicator 6 and three mixing potentiometer controls 8, 9, and 10, is shown intermediate three sound reproducers indicated at A, B, and C, and a loud speaker 4. The output of reproducer A is shown connected over conductors 12 to the mixing potentiometer 8; the output of reproducer B is shown connected over conductors 13 to the mixing potentiometer 9; and the output of reproducer C is shown connected over conductors 14 to the mixing potentiometer 10. The output of the three potentiometers is then combined and fed over conductors 15 to the loud speaker 4, the level of the combined outputs of the reproducers being indicated by the neon tube volume indicator 6. Under each mixing potentiometer 8, 9, and 10, are shown button switches A', B', and C', respectively, which are connected by conductors 16, 17, and 18, to the respective reproducers A, B, and C. Above the potentiometer 9, another button D is illustrated, which is connected by single line conductors to conductors 16, 17, and 18.

Referring now to Fig. 2, the marking element located in each one of the reproducers A, B, and C is shown as including a guide rod 20 mounted in a support 21, which may be part of the sound reproducing frame or any other support within the reproducer. Fixedly mounted to the other end of the guide rod 20 is an electromagnetic coil 23 shown connected to a source of energy such as a battery 24 by a circuit which includes a switch 25. Slidably mounted upon the guide rod 20 is an iron core or armature 26 to which is attached a bracket 29 by any suitable means, such as screws 30. Attached to the lower end of the bracket is a cup 32, to the inner surface of which a tube 33 is fastened in any suitable manner, such as by welding or riveting. Within the tube 33 and extending beyond the ends thereof is a wick 35, one end of which dips into marking ink in the cup 32, the surface of the ink being indicated at 36. A cover 37 is provided for the cup 32. A film 38 is shown positioned in front of the outer end of the wick. A restoring spring 40 is connected between the bracket 29 and an arm 41 attached to the support 21.

From the above, it will be apparent that the closure of the switch 25 will energize coil 23 which will draw the armature 26 to the right until it is stopped by the end of coil 23. This movement is sufficient to bring the outer end of the wick 35 in contact with the film 38 to mark it. A modification of the wick and ink arrangement is illustrated in Fig. 4 wherein the armature 26 has suit-

ably attached to its lower surface a bracket 43 which supports at its outer end a clamp 44 in which a crayon pencil 45 is held. In this manner, a crayon mark may be impressed upon the film in place of the ink mark as shown in Fig. 2.

Referring now to Fig. 3, this schematic drawing illustrates the circuit arrangement for the three reproducers of Fig. 1. Coils A'', B'', and C'', associated with respective markers such as shown in Fig. 2, are controlled individually by respective switches A', B', and C', as shown in Figs. 1 and 3, while switch D simultaneously energizes all three coils. A battery source 46 supplies the actuating energy for all markers. Therefore, should it be desired to operate only the marker associated with coil A'', then only switch A' will be closed, and likewise for the other two markers. Should it be desired to operate all three markers simultaneously, then only switch D need be actuated, which simultaneously energizes all three of the coils A'', B'', and C''. Thus, the mixer may, during a rehearsal, mark any one of the films in the respective reproducers or all three films simultaneously by simply pressing the proper button immediately adjacent his mixer potentiometer.

Since the mixer usually has his hand on a potentiometer knob, during rerecording, he can very quickly push the proper button after he hears the unwanted sound. Since each marker unit is positioned so as to mark the film after it passes the translation point, the mixer can press the button switch so that the beginning of the mark is nearly always immediately adjacent the point on the film to be inspected. The marking point is preferably located approximately eight frames from the translation point, since the time taken for the film to travel this distance is the average time required for a mixer to actuate the marking button. The pressing of the switch may be only momentary, the release of the switch discontinuing the mark since the restoring spring 40 of each of the markers will remove the marking element from the film.

Although the marking unit shown in Fig. 2 has been described in connection with a rerecording system, it is to be understood that it may also be attached to a camera, projector, or sound recorder, if it is desired to mark the films in these devices. It is to be further understood that although the invention has been illustrated and described as embodied in three reproducers, that any number of reproducers may be similarly controlled and their films marked.

I claim as my invention:

1. A film marking system for a sound rerecording system having a plurality of sound reproducers, a loud speaker for reproducing the sound from said reproducers and a potentiometer for each of said reproducers adapted to vary the volume of the sound therefrom, comprising a film marking unit associated with at least one of said reproducers, and switch means for said marking unit for actuating said marking unit to mark said film, said switch means being located adjacent the potentiometer for said respective reproducer.

2. A film marking system for a sound rerecording system having a plurality of sound reproducers, a loud speaker for reproducing the sound from said reproducers and a potentiometer for each of said reproducers adapted to vary the volume of the sound therefrom, comprising a film marking unit associated with each of said reproducers, and individual switch means for each

of said markers for actuating said markers to mark said film, the respective switch for each of said markers being located adjacent the potentiometer for said respective reproducer.

3. A sound rerecording system in accordance with claim 2 in which a master switch is provided for simultaneously actuating the film markers in all of said reproducers.

4. A system for marking one or more moving films being reproduced by a plurality of sound reproducers for simultaneously translating sound film records into corresponding electrical currents, a loud speaker for translating said currents into sound waves and a potentiometer for each of said reproducers for varying the amplitude of the currents from each of said reproducers, said marking system comprising means in each of said reproducers for placing a mark on each of said films, a control means for each of said marking means positioned adjacent the potentiometer controlling the electrical currents from said respective reproducer, and means interconnecting each of said marking means and its respective control means for actuating said marking means during reproduction of said films to cause a respective film to be marked.

5. A system in accordance with claim 4 in which an additional control means is provided for simultaneously actuating all of said marking means.

6. A system in accordance with claim 4 in which said marking means comprises an electromagnet and a marking element actuated by said electromagnet and adapted to contact moving film adjacent thereto upon energization of said electromagnet.

7. A film marking system for a rerecording sound system having a plurality of means for translating a corresponding plurality of sounds records into electrical currents, means for translating said currents into sound waves and a volume control means individual to and interconnecting each of said first mentioned means with said second mentioned means, said marking system comprising means individual to each of said first mentioned translating means for placing a mark on said sound records, and means individual to each of said marking means for the actuation thereof.

20 8. A system in accordance with claim 7 in which each of said last mentioned actuating means is positioned adjacent its respective volume control means for rapid operation of said actuating means during operation of said volume control means.

25 9. A system in accordance with claim 7 in which an additional actuating means is provided for the simultaneous actuation of all of said marking means.
